UNITED STATES PATENT OFFICE.

JOHN F. ROTHFUS, OF HAMMONTON, NEW JERSEY, ASSIGNOR TO FIGUEROA CUT GLASS CO., OF HAMMONTON, NEW JERSEY, A CORPORATION OF NEW JERSEY.

DESIGN FOR A CUT-GLASS VESSEL.

46,652.

Specification for Design.

Patented Nov. 17, 1914.

Application filed June 13, 1914. Serial No. 845,029. Term of patent 7 years.

To all whom it may concern:

Be it known that I, JOHN F. ROTHFUS, a citizen of the United States, residing at Hammonton, Atlantic county, New Jersey, have invented a certain new, original, and ornamental Design for Cut-Glass Vessels, of which the following is a specification, reference being had to the accompanying drawing, forming part thereof.

The figure is a plan view of a portion of a cut glass dish, the other portion being identical therewith, showing an ornamental spray

of daisies exemplifying my new design for such vessels which comprises a floral pattern in imitation of a daisy, with the petals shown in opaque lines.

I claim:

The ornamental design for a cut glass vessel, as shown and described.

JOHN F. ROTHFUS.
